US0D1049277S

(12) **United States Design Patent** (10) Patent No.: **US D1,049,277 S**
(45) Date of Patent: ** Oct. 29, 2024

(54) **ERGONOMIC GYM GRIP**

(71) Applicant: **Lucas Tan**, Orchard Wharf (GB)

(72) Inventors: **Daniel Dobrogorsky**, St Albans (AU);
Jason Tan, Ravenhall (AU)

(**) Term: **15 Years**

(21) Appl. No.: **35/519,485**

(22) Filed: **Dec. 6, 2023**

(80) **Hague Agreement Data**

Int. Filing Date: **Dec. 6, 2023**

Int. Reg. No.: **DM/233855**

Int. Reg. Date: **Dec. 6, 2023**

Int. Reg. Pub. Date: **Dec. 22, 2023**

(51) **LOC (14) Cl.** **21-02**

(52) **U.S. Cl.**

USPC **D21/694**

(58) **Field of Classification Search**

USPC D21/694, 662, 682, 684; D12/114;
D8/303
